UNITED STATES PATENT OFFICE.

LEBRECHT FRITZSCHE, OF NEWARK, NEW JERSEY, ASSIGNOR TO RICHMOND BROTHERS COMPANY, A CORPORATION OF NEW JERSEY.

DESIGN FOR A CANDY-TONGS MEMBER.

No. 39,508.

Specification for Design.

Patented Sept. 8, 1908.

Application filed March 17, 1908. Serial No. 421,747. Term of patent 7 years.

To all whom it may concern:

Be it known that I, LEBRECHT FRITZSCHE, a citizen of the United States, residing at Newark, in the county of Essex and State of New Jersey, have invented a new, original, and ornamental Design for Candy-Tongs Members, of which the following is a specification, reference being had to the accompanying drawing, forming part thereof, and the single figure of which shows in perspective a member of a candy-tongs having my new design.

I claim:

The ornamental design for a candy tongs member, as shown.

LEBRECHT FRITZSCHE.
